UNITED STATES PATENT OFFICE.

JOHN J. CATRON, OF BONHAM, TEXAS.

VENT DEVICE.

1,391,245.

Specification of Letters Patent. Patented Sept. 20, 1921.

Application filed July 28, 1919. Serial No. 313,922.

To all whom it may concern:

Be it known that I, JOHN J. CATRON, a citizen of the United States, residing at Bonham, in the county of Fannin and State 5 of Texas, have invented certain new and useful Improvements in Vent Devices, of which the following is a specification.

This invention relates to new and useful 10 improvements in hose devices for gasoline dispensers to vent the hose and prevent air locks in the hose and to admit air into the hose to drain the same.

Where a tank is filled at a higher elevation 15 than the bend in the drain or filling hose, an air lock is likely to occur between the lowest point in the hose and the dispenser. In order to overcome this trouble and also to obviate the use of a drain-hose valve, I employ a small tube for venting 20 located between the cut-off at the dispenser and the connecting end of the hose and carry this tube to an elevation higher than the overflow of the measuring cylinder or accumulating cylinder.

25 In carrying out the invention a small vent tube is connected into the top of the elbow with which the drain-hose is connected. The upper end of the tube being tapped into the top of the measuring cylinder above the 30 overflow thereof. When the supply is cut-off this tube vents the drain-hose.

The invention will be more readily understood from a reading of the following specification and by reference to the accompanying 35 drawings, in which an example of the invention is shown and wherein:

Figure 1 is a view of the upper portion of 40 a gasoline dispenser embodying the invention, and

Fig. 2 is an elevation of the supply and over-flow connections.

In the drawings the numeral 1 designates a gasoline supply pipe which is connected to a two-way T 2, having its upper end connected with a measuring cylinder by a pipe 3. From one of the branches of the T 2, a drain pipe 4 extends. The pipe 4 includes a drain valve 5 and connects with a main drain pipe 6. An overflow pipe 6' extends 45 from within the measuring cylinder down to the pipe 6. From the other branch of the T 2, a discharge pipe 7 extends to a down-turned elbow 8 and includes a cut-off valve 7'. A drain hose 9 leads from the lower end 50 of the elbow 8.

The gasoline or other liquid is forced into

the measuring cylinder from pipe 1 through T 2 and pipe 3, the valve 7' being normally closed. By opening the valve 7' the liquid from the cylinder flows out through pipe 3, 60 T 2, pipe 7 and valve 7' to elbow 8, from which it is conveyed by the hose 9 to the point of discharge. The liquid is under air pressure as it enters the cylinder, but this is cut off and the liquid flows from the cylinder 65 by gravity. When the valve 7' is opened and the hose is held so that a bend is had, as in filling tanks on trucks or at other high elevations, an air lock is likely to occur between the bend in the hose and valve 7'. I 70 use the tube 10 to vent the air from the air lock which would otherwise have to pass to the gasoline in the glass cylinder, causing the gasoline to flow very slowly through the 75 hose. Particular attention is called to the fact that the tube 10 has its bore unobstructed 75 so that the air may pass therethrough in opposite directions.

My improvement consists mainly in an upright vent tube 10 having its lower end connected in the top of elbow 8 and its upper end passed through and tapped into the top 11 of the cylinder. The top of the tube being above the top of the overflow pipe 6' can never be covered by the liquid. When the 80 valve 7' is cut off air may enter the vent tube and the hose 9 and drain the hose. No drain-hose valve is necessary and a plain nozzle may be used as the air vent will cause the 85 liquid to flow freely through the hose and 90 drain therefrom.

When the hose 9 has its discharge end elevated above the elbow 8, or when a vertical bend occurs in the hose, a portion is formed 95 which is approximately U-shaped. If the valve 7' is partly opened, the gasoline may flow through the hose 9 into this vertical U-shaped portion, and this gasoline may not completely fill the cross-sectional area of the 100 hose. The vertical U-shaped portion of the hose becomes filled with the gasoline, without expelling the air within that portion of the hose between the U-shaped portion and the elbow 8, whereby the air becomes 105 entrapped in this portion and forms an air lock. As the portion of the hose between the U-shaped portion and the elbow 8 begins to fill with gasoline, the air would ordinarily be forced back through the elbow, valve 7', and pipe 3, and caused to travel upwardly 110 through the gasoline. This would retard the flow of the gasoline through these parts. In

my device, this cannot occur, as the air entrapped behind the U-shaped portion of the hose will vent through tube 10 into the top of the cylinder 11. When the valve 7' is closed, and it is desired to lower the hose 9 and drain it, air passes inwardly through the tube and enters the hose 9.

What I claim, is:

1. In apparatus of the character described, 10 the combination with an upstanding receptacle having a bottom provided with a flange and an air space in its upper end, of a valve discharge fitting arranged beneath the bottom and flange and leading from the bottom 15 of the receptacle, a vent pipe having a permanently open bore so that air may pass therethrough in opposite directions, said vent pipe being connected with the fitting at a point beneath the bottom and rising therefrom and passing through the flange and having its upper intake end leading into the air space in the top of the receptacle, and a 20 discharge conduit connected with the fitting.

2. In apparatus of the character described, 25 the combination with an upstanding receptacle having a bottom and an air space in its top, of a valve discharge fitting arranged beneath the bottom and covered thereby and leading into the receptacle, a vent pipe having a permanently open bore to permit of 30 the passage of air therethrough in opposite directions, said pipe being connected with the fitting adjacent the valve and at a point covered by the bottom and rising therefrom 35 and having its upper intake end leading into the interior of the receptacle at the air space in the top thereof, and a discharge conduit connected with the fitting.

3. In apparatus of the character described, 40 the combination with a receptacle, of a gravity liquid discharge pipe, having connection with the receptacle, a valve connected in said pipe, a drain hose connected with the pipe, and a tube connected with said pipe adjacent to said valve and leading into the upper portion of the receptacle, said tube having its bore permanently open to permit of the 45 passage of air therethrough in opposite directions.

4. In apparatus of the character described, 50 the combination with a receptacle, of a gravity liquid discharge pipe connected therewith, a valve connected in said pipe, a drain hose connected with said pipe, an upstanding overflow pipe arranged within the receptacle, and a tube connected with the gravity liquid discharge pipe at a point near said valve and extending upwardly above the top 55 of the overflow pipe, said tube having a permanently open bore to permit of the passage of air therethrough in opposite directions.

5. In apparatus of the character described, 60 the combination with a receptacle, of a gravity liquid discharge pipe having connection 65 with the receptacle, a valve connected in said pipe, a drain hose connected with the pipe, and a tube connected with said pipe near said valve and extending upwardly beyond the maximum level of the liquid within the said receptacle, said tube having its bore permanently open to permit of the 70 passage of air therethrough in opposite directions.

In testimony whereof I affix my signature. 75
JOHN J. CATRON,
